UNITED STATES PATENT OFFICE.

SERGIUS BESSONOFF, OF PAVLOVSK, NEAR ST. PETERSBURG, RUSSIA.

BOILER-FEED PURIFIER.

1,081,935.

Specification of Letters Patent.

Patented Dec. 16, 1913.

Application filed December 16, 1912. Serial No. 737,111.

To all whom it may concern:

Be it known that I, SERGIUS BESSONOFF, a subject of the Emperor of Russia, residing at 1 Katherinastrasse, Pavlovsk, near St. Petersburg, in the Empire of Russia, have invented a certain new and useful Improvement in Boiler-Feed Purifiers, of which the following is a specification.

The present invention has for its object 10 an apparatus which is arranged in the boiler below the water level for eliminating the boiler scale in the feed water by heating the latter by means of steam bubbles which ascend in the water chamber and are received 15 by the apparatus in such a manner that the steam passes through the entire mass of the water which fills the apparatus, so that the water is heated to a temperature approximating the boiling point in the boiler. The 20 boiler scale which deposits on the bottom of the apparatus in a powdered condition is periodically discharged therefrom by means of discharge pipes arranged in the apparatus. The steam bubbles ascending in the 25 water chamber are collected by the troughs or plates which are arranged within the water chamber, the collected steam escaping through a longitudinal slot approximately half way up the apparatus. This slot is of 30 such a size that only the quantity of the steam resulting from the single bubbles entering the apparatus from below can pass through it. As a result of this, the steam on the face of the slot is at a pressure higher 35 than that in the steam chamber, and therefore it is able to penetrate the mass of water which fills the apparatus, while, on the other hand, the water will not circulate downward through the slot.

40 The invention is illustrated in the accompanying drawing, in which:

Figures 1 and 2 represent the thermic apparatus arranged in a boiler in vertical cross section. Fig. 3 is a vertical longitudinal section on the line 3—3 Fig. 1, and Fig. 4 is a horizontal section on the line 4—4 Fig. 2.

The apparatus embodying the invention preferably consists of three parallel series 50 of boxes A_1 , A_2 , etc., of the cross section illustrated in Fig. 1, the ends of which are inserted one within the other. These boxes are fixed in the boiler below the water level in any convenient manner, for example as 55 represented in the drawing, by placing the

separate boxes on two parallel angle irons to which each box is secured by means of screws. The angle irons themselves are fixed to the flanges of the flues. All the middle boxes present only longitudinal 60 walls, but the two extreme boxes have end walls. The boxes taper slightly or are restricted to one end, so that they may be fitted one within the other. The bottom of this apparatus comprises recesses which 65 merge upward into three longitudinal slots a , b and c . The outside slots a and c have strips d and f at a certain distance above them, while a channel or trough g is fixed above the middle slot b on uprights s , the 70 front ends of the channel or trough g being connected with the feed pipe h through which the feed water is supplied. Two pipes h and l each closed at one end are arranged in the recesses at the bottom of the 75 two lower troughs. These pipes are provided with perforations throughout their entire length and are branched off a single pipe r which passes outside the boiler and is provided with a cock m .

80 The apparatus described above operates in the following manner:—The water which is supplied through an appropriate feed water apparatus passes through the feed pipe h into the channel g from which it 85 overflows more or less uniformly over the upper edges into the troughs or boxes located on each side of the channel g . The steam collecting on the heating surface of the boiler in the planes of the slots a , b and 90 c is at a pressure which is higher than the pressure which prevails in the steam chamber of the boiler, as already explained. It is therefore able to overcome a certain amount of resistance and to penetrate through the 95 entire quantity of water which fills the apparatus, while the water is unable to pass through the slots in opposition to the current of steam. As experiments have demonstrated, water which contains salts forming 100 hard boiler scale, when heated by the direct introduction of steam, deposits this boiler scale in the form of a very fine amorphous powder. The heated water (from which the boiler scale has already been separated) is 105 gradually forced from the apparatus owing to the water leaving the channel g and flows over the upper part of the apparatus into the common water chamber of the boiler. The steam in excess which has not con- 110

densed in the apparatus passes from the latter into the steam chamber of the boiler. The boiler scale separated from the water is periodically discharged through the pipes *k* 5 and *l* by opening a discharge cock *m*.

As the entire apparatus is located in the water chamber of the boiler the driving forces which impel the water which fills it to pass into the water chamber are inconsiderable, because they represent merely differences between the specific weights of the 10 hotter and the cooler water.

The several parts of the apparatus do not require tight joints, it being sufficient to insert the end of one into the end of the other. 15

What I claim and desire to secure by Letters Patent of the United States is:—

1. A feed water apparatus for boilers, comprising a plurality of troughs extending longitudinally of the boiler and located below the water level of the boiler, means for supplying water to said troughs along substantially their entire length, means for directing steam onto the contents of said 20 troughs said means extending along a side of each of said troughs, and means for removing the powdered material collecting in said troughs.

2. A feed water apparatus for boilers,

comprising an upper trough, means for feeding water thereto, a lower trough arranged on each side of said upper trough and adapted to contain the water overflowing from same, means for collecting steam rising through the boiler, means for directing such collected steam onto the water contained in the said lower troughs, and perforated conduits located in the said lower troughs to remove the material deposited therein. 30

3. A feed water apparatus for boilers, comprising an upper trough, means for feeding water thereto, a lower trough located at each side of said upper trough, the under surface of said troughs being formed to collect the steam rising through the boiler, and plates located adjacent to an edge of each of said lower troughs and extending for the entire length of same, said plates serving to direct the collected steam 35 onto the water within said lower troughs. 40

In testimony whereof I affix my signature in presence of two witnesses.

SERGIUS BESSONOFF.
